WILLIAM MACGOWAN, OF ARDROSSAN, SCOTLAND.

LETTER-FILE.

SPECIFICATION forming part of Letters Patent No. 719,350, dated January 27, 1903.

Application filed March 11, 1902. Serial No. 97,754. (No model.)

To all whom it may concern:

Be it known that I, WILLIAM MACGOWAN, marine surveyor, a subject of the King of Great Britain and Ireland, and a resident of 5 Ardrossan, Ayrshire, Scotland, have invented certain new and useful Improvements in Letter-Files, (for which I have made application for a patent in Great Britain, No. 18,047, dated the 10th of September, 1901,) of which 10 the following is a specification.

The objects of my invention are improvements in letter-files which will afford a convenient method of keeping letters or other documents alphabetically arranged and so 15 that they are capable of instant reference as required.

Referring to the drawings which form a part of this specification, Figure 1 is a front elevation of a letter-file constructed in accordance with my improvements. Fig. 2 is 20 a side view of same. Fig. 3 is a back view of the wire frame and spring arrangement at the upper part of the letter-file.

In carrying into practice the improvements 25 of this invention the letter-file consists, essentially, of a number of separate sheets 1 of stout paper, parchment, or any suitable flexible material imposed one above the other, the top sheet 2 being of stouter material, 30 forming a cover and retained in position as will be described. The upper sheet or cover 2 is strengthened at its upper or free end by a thin sheet 3 of tin or other metal or material clamped or otherwise secured to it. This 35 sheet of metal is marked with the letters of the alphabet and is formed as a plate extending and clamped over the upper edge of the sheet and has several parts 4 projecting downward toward the center of the sheet, 40 which parts are corrugated or formed with ridges. Projecting tabs 5 are secured to each sheet, or formed in one with each sheet, of the series 1, of disk form, as shown, and each is marked with a letter of the alphabet 45 for the purpose of distinguishing and raising the desired sheet under which the letter is to be placed or to be consulted and also for the purpose of enabling these alphabetically-marked tabs to be readily manipulated by 50 seizing with the thumb and fingers in an ordinary manner. These alphabetically-marked tabs are secured to the sheets and arranged

in a stepped manner in order that the whole alphabet be shown of a reasonable size. When the strengthening metal sheet 3 of outer sheet 2, or the sheet 2 itself, is marked with the letters of the alphabet, these would be placed so as to be opposite to or coincide with the letters on the tabs, as shown. To securely hold the series of sheets 1 thus fitted with 55 tabs and the outer sheet 2, two holes are formed near their lower edges, where they may be reinforced by perforated disks of paper, cloth, leather, or other material, and the sheets are placed on two wires 7, fitted to 60 the wooden or other sole plate 8, supporting the whole. These two wires 7 are bent at right angles and made to swivel on the sole-plate, so that their ends may engage with one another, being angled or beveled for this purpose and forming, with the sole-plate 8, a frame 65 of rectangular form. After the sheets are placed on the wires the two ends can be made to engage by swiveling each wire toward the other. A small rubber ring 6 is tightly fitted 70 on each perpendicular arm of this wire frame 7 above cover 2 when in place for the purpose of pressing down and holding sheets and contents in compression. The lower edge of the cover 2 is also reinforced by a thin sheet 9 of metal clamped to it and perforated 75 with two holes for the wires 7. The file is thus secured to the sole-plate 8, and this is fitted at its upper end with a casing 10, formed with an eye by which the file may be hung 80 up, within which the ends of a wire frame 11 enter by elongated holes in the ends of casing, where they are bent, as shown, and the ends connected by a sleeve and engage with reaction springs 12 within. The wire frame is 85 also bent outside of casing to form cams 13 to engage with projecting parts of the casing 10, so that the frame may be held up by the action of the spring while letters are being inserted or pressed normally down on the top 90 of the file by the action of the springs 12. When pressed down on the top of the file, the cross-bar 14 of the frame 11 will lie on the corrugated parts 4 of the strengthening-sheet 95 3 of metal, already described. The wire frame 10 is also bent at each side in loop form at 15 for the purpose of entering slots in the sole-plate 8, by which means letters or other documents are prevented from falling out sidewise from

between the sheets of the file. India-rubber studs 28 are secured to the base-plate near each corner.

I claim as my invention—

- 5 1. A letter-file comprising a flat base-plate having two upright wires near one edge, each swiveled at its lower end to the base-plate, the upper free ends of the wires being bent and beveled at their outer ends and adapted 10 to be turned into position with the bent ends parallel to receive letters, in combination with a sheet having two perforations near its edge, said sheet adapted to be placed with its two perforations on the two hooked ends in their 15 parallel position and slid along toward the swiveled ends, whereby on placing the hooked ends in line with each other the sheet will be secured in position on the upright wires, substantially as described.
- 20 2. A letter-file comprising a base-plate, sheets secured thereto, a pivoted frame mounted on the upper face and at one end of the base-plate, looped parts to said frame adapted to extend past the sheets at their outer edges 25 at right angles, whereby the sidewise motion

of the sheets is prevented, substantially as described.

3. A letter-file, comprising a base-plate having slots near one end, and a pivoted frame having looped parts passing through the slots, 30 substantially as described.

4. A letter-file, comprising a base-plate, a top sheet therefor, a metal-reinforced end for said top sheet, corrugations on the reinforced metal end and a pivoted frame to engage with 35 the corrugations, substantially as described.

5. A letter-file having a base-plate, sheets secured thereto at one end, said sheets being alphabetically tabbed, and the top sheet having a reinforced metal part, with corrugations, 40 in combination with a spring-pressed frame, substantially as described.

In testimony whereof I have signed my name to this specification in the presence of two subscribing witnesses.

WILLIAM MACGOWAN.
